UNITED STATES PATENT OFFICE.

EDWARD MOORE WALLACE, OF NEW ORLEANS, LOUISIANA.

BAG CLOSURE AND CARRIER.

1,079,527.

Specification of Letters Patent. Patented Nov. 25, 1913.

Application filed April 3, 1913. Serial No. 758,595.

To all whom it may concern:

Be it known that I, EDWARD MOORE WALLACE, a citizen of the United States, residing at New Orleans, in the parish of Orleans and State of Louisiana, have invented certain new and useful Improvements in Bag Closures and Carriers; and I do hereby declare the following to be a full, clear, and exact description of the invention, such as will enable others skilled in the art to which it appertains to make and use the same.

This invention appertains to certain new and useful improvements in bag closures and carriers, the object of the invention being to provide a simple, cheap and effective device for closing carrying or hanging bags made either of paper or textile fabric with the contents of the bag.

A further object of my invention is to provide, a bag closure and carrier or hanger having flat or plane surfaces which may be used to print or impress thereon advertising matter, and having such end in view the bag closure and carrier is preferably made from a flat piece of material as cardboard which will serve the purpose well and admits of the article being manufactured at such a low cost that it may be given away by merchants.

In the accompanying drawings which illustrate a preferred form of my invention, Figure 1 is a front elevation of the bag closure and carrier, Fig. 2 is a vertical section on the line 2—2. Fig. 3 is a section with a bag in position showing the device used as a closure and hanger. Fig. 4 is a front elevation with a bag in place and Fig. 5 is a view showing the device used as a bag closure and carrier.

Referring to the drawings, a flat blank 1 is cut or stamped to have a suitable marginal configuration, preferably as shown with rounded ends and parallel sides; the blank being of such size as to admit of having formed therethrough an opening 2 of such size as to provide for the passage of a part of the bag and of the fingers of a person's hand. The opening 2 is preferably oval and below the same is a smaller opening 3 which may be of the same shape as the one above, substantially as shown by the drawings.

The blank with the openings 2 and 3 forms a complete article of manufacture or sale and when made of cardboard the opposite flat surfaces may be printed upon so that the bag closure and carrier not only serves its primary purpose, but may also be used

as an advertising device. Instead of making the device of cardboard it may be of wood or sheet metal and when of the latter material the advertising matter may be embossed upon the blank.

In practice the paper or textile bag 4, in which the merchandise or article has been placed is folded or crimped by grasping the neck thereof with the hand, the compressed or gathered-in end is passed through the larger opening 2 and then through the smaller opening 3, the bag forming a loop about the central part 5 of the blank. When the bag has been placed in engagement with the closure and carrier the depending end of the bag will be pressed against the lower portion of the blank, below the opening 3 which tends to prevent the gathered end of the bag slipping so that the weight of the bag and its contents will be suspended by the looped portion contacting with the lower edge of the opening 2. The lower curved edge of the opening 2 causes the material to center and leaves ample space above the fold for the insertion of the fingers when used as a carrier, and when used as a hanger the device will center itself. By providing rounded or oval openings or apertures through the blank I avoid sharp edges which would be liable to cut the paper bag.

It will be noted that the shape of the blank or body portion of the bag closure and carrier or hanger may be varied as well as the shape of the openings, but in every instance it is desirable to have the lower aperture of a smaller size than the one above, therefor the design may be varied to accord with the use or business of the user.

I claim—

1. As a new article of manufacture, a bag closure and carrier comprising a flat one piece body portion that is provided with openings of different sizes the larger opening being of a size to admit therethrough the fingers of a person and to provide above the opening a grasping portion the openings having between them a curved wall which separates the two openings.

2. A bag closure and carrier comprising a flat piece of material having rounded ends and oval apertures of different sizes, one of the apertures being of a size to provide a hand grasping portion between the aperture and one end, for use in closing, sustaining or carrying a bag when the gathered end thereof is passed through the larger aperture and

then through the smaller one substantially as described; so that the weight of the contents of the bag will press its end portion against the opposite flat surface of the closure and carrier.

3. A bag closure comprising a card-board body portion having therethrough within its perimeter elliptical apertures of different areas which are separated by an intermedi-

ate integral part the contour of which is 10 concave to provide curved bearing surfaces for a gathered and looped end portion of a bag.

EDWARD MOORE WALLACE.
